HUM REDUCTION

Robert B. Dome, Bridgeport, Conn., assignor to
General Electric Company, a corporation of New
York

Application October 26, 1938, Serial No. 237,024

6 Claims. (CL 250—27)

My invention relates to electron discharge circuits and more particularly to means for reducing so-called hum currents in such circuits.

Electron discharge devices in which the cathodes are heated by alternating current applied to a heater within the cathode are subject to the objection that current having the frequency of the heating currents are produced in the output of the discharge device. These currents are commonly referred to as hum currents. One of the objects of my invention is to reduce the production of these hum currents.

Such hum currents are produced by reason of a number of different effects. It has been found in accordance with my invention that they may be produced by reason of capacity existing between the lead-in conductors of the grid and heater of the discharge device. It has also been found in accordance with my invention that the heater may act as a grid within the discharge device to vary the current flowing from the anode to the cathode.

One of the objects of my invention is to reduce the hum currents produced by either of these effects.

Another object of my invention is to supply to the grid of the electron discharge device an electromotive force tending to neutralize the effect of the heater element acting as a grid within the discharge device.

The novel features which I believe to be characteristic of my invention are set forth with particularity in the appended claims. My invention itself, however, both as to its organization and method of operation, together with further objects and advantages thereof may best be understood by reference to the following description taken in connection with the accompanying drawing in which Fig. 1 represents an embodiment of my invention; Fig. 2 represents a structural detail of an electron discharge device in connection with which my invention may be employed; and Fig. 3 represents a modification of my invention.

Referring first to Fig. 2 of the drawing, I have indicated therein the arrangement of the lead-in conductors of an electron discharge device in connection with which my invention may be employed. This figure represents the base of an electron discharge device having projecting therefrom a number of terminals 1 to 8 inclusive, certain of these terminals, of course, being connected to electrodes within the discharge device through lead-in conductors. I have also indicated on this drawing by suitable legends the electrode to which the respective terminals are connected. The shell

or metal envelope of the discharge device, which is connected to the terminal 4, is commonly connected through external connections to the heater terminal 3 and to ground because of the greater convenience of wiring adjacent terminals together. The opposite heater terminal 7, it will be observed, is adjacent the control grid terminal 6. I have found that the capacity between these two terminals, or more particularly between the lead-in conductors extending from these terminals up through the glass seal, which capacity I have indicated by dotted lines 9 in the figure, is sufficient to induce into the grid circuit of the discharge device an objectional amount of voltage from the heater circuit. In fact, this voltage after amplification in two or three amplification stages may amount to as much as 10 volts and is thus decidedly objectionable. I have found that this voltage may be very substantially reduced by grounding the heater terminal 7 through the external connections, this terminal being the one nearer to the control grid. The shell terminal 4 is then connected to terminal 7, and terminal 3 is of course not grounded.

In fact, this change in circuit connection has been found to reduce the hum voltage produced by the capacity 9 to as low as one quarter of its initial value.

In Fig. 1 I have shown the circuit embodying my invention in more complete detail. In this figure I have shown an electron discharge device 10 having a cathode which is connected through a cathode bias resistor 11 to ground and to the terminal 7 of the heater. It is also connected through terminal 4 to the envelope of the electron discharge device. The source of heating current which is represented by the cathode transformer 12 is connected directly across the heater, i. e., between terminals 3 and 7.

The figure also represents an input circuit of 40 the discharge device comprising an input coupling condenser 13 and resistance 14, the latter of which is connected between the control grid and cathode of the discharge device through the bias resistor 11. An output circuit is shown comprising the coupling condenser 15, anode coupling resistor 16, and source of anode potential 17. Screen grid potential for the discharge device is supplied by the source 18. The sources 17, 18, and similarly the cathode bias resistor 11, are bypassed for currents to be amplified by the discharge device, by condensers 19, 20, and 21 respectively.

With the connections shown it will be observed that due to the cathode heating current supplied 55

by transformer 12, the potential of the heater varies cyclically with respect to the potential of the cathode. I have found that this heater has the effect of a grid within the discharge device 5 in that when its potential varies in the positive direction, the current in the anode circuit increases, whereas when it varies in the negative direction, the anode current decreases.

In accordance with my invention a voltage is 10 supplied between the control grid and the cathode which tends to oppose these variations in anode current. It has been found convenient to supply this voltage across the cathode bias resistor 11, and, in the form of the invention shown 15 in Fig. 1, this is effected by the shunt combination of resistance 22 and capacitance 23, the latter being connected between the cathode of the discharge device and the terminal 3 of the heater. It has been found that by properly proportioning this resistance and condenser relative 20 to the resistance 11 and condenser 21, a voltage may be produced across resistance 11 tending to make the grid sufficiently negative with respect to the cathode during the half cycles of the heating current when the anode current tends to increase to just overcome these variations. To effect this, it is merely necessary that the voltage supplied to the cathode through resistance 22 be 25 in phase with the voltage supplied to the heater, and it may easily be shown that this condition obtains when the time constant of resistance 22 and condenser 23 is equal to the time constant of resistor 11 and condenser 21. I have found 30 that by the use of this connection, including resistance 22 and condenser 23, the hum voltage may be reduced to substantially less than half that which is produced when these elements are omitted from the circuit.

Of course the tendency of the anode current 40 to increase due to variation in the heating current is opposed to a slight extent by the potential produced on resistance 11 by the passage of this anode current. That is, an increase in anode current produces a larger potential on resistance 45 11 which, in turn, drives the grid more negative and tends to maintain the anode current constant. This effect, however, is far too small to be of importance in the elimination of hum, and for effective elimination of hum it is necessary 50 to supply a greater voltage across resistance 11 as is done by resistance 22 and condenser 23.

In Fig. 3 I have shown a modification of my invention in which the heating current is supplied from a transformer 12 as in Fig. 1. The 55 secondary winding of this transformer, however, has an intermediate point which is connected to the terminal 7 of the heater, the terminal at one end of the secondary winding being connected to the opposite terminal 3 of the heater, and the 60 other terminal of the secondary winding being connected through grid coupling resistor 14 to the control grid of the discharge device. In this way it will be seen that when the heater is driven 65 positive with respect to ground, thereby tending to cause the anode current to increase, the grid is simultaneously driven negative with respect to the cathode thereby tending to oppose the increase in anode current.

While I have shown a particular embodiment 70 of my invention, it will of course be understood that I do not wish to be limited thereto, since many modifications both in the circuit arrangement and instrumentalities employed may be 75 made, and I contemplate by the appended claims

to cover any such modifications that fall within the true spirit and scope of my invention.

What I claim as new and desire to secure by Letters Patent of the United States is:

1. In combination, an electron discharge device 5 having a grid element, an anode element, a unipotential cathode element, and a heater element arranged to heat said cathode all enclosed in a sealed envelope, lead-in conductors for said elements including a pair of lead-in conductors for 10 said heater element, one of said pair of lead-in conductors for the heater element being physically nearer the lead-in conductor for the grid than the other, an input circuit connected to said grid and cathode lead-in conductors, an output circuit connected to said anode and cathode lead-in conductors, means to ground a point common to said circuits, a source of alternating electro-motive force connected to said pair of lead-in conductors to energize said heater elements, 15 whereby the potential of said one lead-in conductor for said heater element varies with respect to said grid lead-in conductor and due to the capacity therebetween tends to produce undesirable potential variations in said input circuit and resulting undesirable hum in said output circuit, and means to reduce said variations comprising means to ground said one lead-in conductor.

2. In combination, an electron discharge de- 30 vice having a grid circuit, an anode circuit, a unipotential cathode, and a heater for said cathode, an impedance common to said circuits, said impedance being connected between said heater and cathode, means to supply alternating 35 heating current to said heater whereby the potential of said heater varies relative to said cathode and tends to produce corresponding variations in current in said anode circuit, and means to supply across said impedance a voltage 40 having the frequency of the heating current and phased to oppose said variations in anode current.

3. In combination, an electron discharge device 45 having a grid circuit, an anode circuit, a uni-potential cathode, and a heater for said cathode, an impedance common to said circuits, said impedance being connected between said cathode and one side of said heater, means to supply alternating heating current to said heater, and an 50 impedance between the cathode and the opposite side of said heater, said impedances being proportioned to produce on said cathode a voltage of the frequency of the heating currents and phased 55 to oppose variations in anode current produced by variation in potential of the heater relative to the cathode.

4. In combination, an electron discharge de- 60 vice having an anode, a unipotential cathode, a grid, and a heater for said cathode, a circuit between said anode and cathode, a source of alternating energizing current connected across said heater and having one side thereof connected to said cathode whereby the potential 65 of the heater varies with respect to the cathode, and said heater acts as a grid to control the current in said circuit, and means to supply between said grid and cathode from said source, a potential of phase with respect to the cathode 70 potential opposite to that of said heater and of such value that acting on said grid it opposes the effect of the potential on the heater acting as a grid.

5. In combination, an electron discharge device having a grid circuit, an anode circuit, a unipotential cathode, and a heater for said cathode, a resistance common to said circuits, 5 said resistance being connected between said heater and cathode and shunted by capacitance to supply bias voltage from the anode circuit to the grid circuit, a source of alternating current connected across said heater, one side thereof 10 being connected through said resistance to said cathode whereby the potential of said heater varies with respect to said cathode and said heater acts as a grid to control the current in 15 said anode circuit, a resistance connected between the opposite side of said source and said cathode, said resistance being shunted by a capacitance, said last resistance and capacitance having a time constant equal to the time constant of said first resistance and capacitance, 20 whereby a potential is supplied to said grid circuit of proper phase to oppose said effect on the anode circuit of said heater acting as a grid.
6. In combination, an electron discharge device having an anode circuit, a grid circuit, a unipotential cathode and a heater for said cathode, a source of alternating current having an intermediate point thereof connected to one side of said heater, to said cathode, and through said anode circuit to said anode, and points opposite said intermediate point connected to said 10 grid end to the opposite side of said heater respectively, whereby said grid is supplied with a potential with respect to said cathode of opposite phase to that with respect to said cathode which is supplied to said heater and the magnitude of 15 the potential supplied to said grid being just sufficient to neutralize the effect on current in the anode circuit of the potential on the heater with respect to the cathode acting on said heater as a grid. 20

ROBERT B. DOME.

CERTIFICATE OF CORRECTION.

Patent No. 2,223,206.

November 26, 1940.

ROBERT B. DOME.

It is hereby certified that error appears in the printed specification of the above numbered patent requiring correction as follows: Page 1, first column, line 29, for "gird" read --grid--; page 5, second column, line 11, claim 6, for the word "end" read --end--; and that the said Letters Patent should be read with this correction therein that the same may conform to the record of the case in the Patent Office.

Signed and sealed this 14th day of January, A. D. 1941.

Henry Van Arsdale,

(Seal)

Acting Commissioner of Patents.
